UNITED STATES PATENT OFFICE

107,644

DESIGN FOR AN AUTOMOBILE

Eugene T. Gregorie, Plymouth, Mich., assignor to Ford Motor Company, Dearborn, Mich., a corporation of Delaware

Application April 29, 1937, Serial No. 69,059

Term of patent 14 years

To all whom it may concern:

Be it known that I, Eugene T. Gregorie, a citizen of the United States, residing in the city of Plymouth, county of Wayne, and State of Michigan, have invented a new, original, and ornamental Design for an Automobile, of which the following is a specification, reference being had to the accompanying drawings, forming part thereof, in which:

The dominant feature of my design resides in the front end portion.

I claim:

The ornamental design for an automobile, substantially as shown and described.

EUGENE T. GREGORIE.
